[57] CLAIM

The ornamental design for a fisherman's carryall, or
similar article, as shown and described.

DESCRIPTION

FIG. 1 is a front perspective view of a fisherman's car-
ryall, or similar article, showing my new design.

FIG. 2 is a rear perspective view thereof.

FIG. 3 is a front elevational view thereof, drawn to a
reduced scale.

FIG. 4 is a left side elevational view.

FIG. 5 is a top plan view.

FIG. 6 is a rear elevational view thereof.

FIG. 7 is a right side elevational view.

FIG. 8 is a bottom plan view.
